Patented Apr. 11, 1922.

INVENTOR
Henry M. Loomer

UNITED STATES PATENT OFFICE.

HENRY M. LOOMER, OF BEVERLY, MASSACHUSETTS, ASSIGNOR TO UNITED SHOE MACHINERY CORPORATION, OF PATERSON, NEW JERSEY, A CORPORATION OF NEW JERSEY.

CUTTER.

1,412,084.

Specification of Letters Patent. Patented Apr. 11, 1922.

Application filed October 7, 1918. Serial No. 257,203.

To all whom it may concern:

Be it known that I, HENRY M. LOOMER, a citizen of the United States, residing at Beverly, in the county of Essex and State 5 of Massachusetts, have invented certain Improvements in Cutters, of which the following description, in connection with the accompanying drawings, is a specification, like reference characters on the drawings indicating like parts in the several figures.

This invention relates to cutters and is illustrated by way of example as embodied in heel trimming cutters especially designed for use in heel trimming machines, although 15 the invention is not limited to such use.

The cutters used in heel trimming machines of certain types are clamped edge-wise in cutter heads carried by the machines. Such cutters are elongated plates 20 of steel sharpened at one end and they are ground back on that end as they become dull. They are in many cases ground back so far by repeated sharpening that not enough length remains to give the clamping 25 mechanism a firm grip on them, with the result that the cutters sometimes fly out of the heads and seriously injure the operators. The likelihood of flying out is greatly increased by the fact that such cutters rotate 30 at high speed, for example, 7000 R. P. M.

It is a principal object of my invention to provide a cutter with means adapted to guard against use when the cutter has been ground to a predetermined limit of safety. 35 An important feature of the invention consists in a cutter marked to indicate the safe limit of grinding. In the illustrated embodiment the cutter is formed in such manner that grinding it beyond the point of 40 safety will alter the cutting edge so that the latter will be rendered unfit for trimming as desired.

This and other features of the invention, including certain details of construction, 45 will be apparent from the following description of one embodiment of my invention, and will then be defined in the accompanying claims.

In the drawings,—
50 Fig. 1 is a perspective of a cutter embodying my invention;

Fig. 2 is a view of the under side of the cutter, and

Fig. 3 shows the cutter in the heel trimming machine.

The machine has a shaft 10 adapted for rapid rotation, and carrying a cutter head plate 12. This plate has two ribs 14 and 16, circular-arcuate in form with their centers lying beyond the center of the shaft 60 10, in each case. The cutters 18 are curved and have notches 20 in their edges adapted to fit over the ribs 14, 16 and similar ribs on a second clamping plate not shown, between which and the plate 12 they are 65 securely clamped. An abutment plate 22 is mounted in the head to position the cutters by contact with their rear ends 24. As the cutting edges 26 become dull the cutters are ground back and the abutment plate is 70 turned forward, thus gradually moving the cutters forward on the ribs 14, 16 in order to keep the cutting edges 26 at the same position on the head. The mechanism so far described is all well known and need 75 not be further discussed.

It has been found that operators will grind the cutters back too far before discarding them, in order to save time and expense. This practice results sometimes 80 in making the cutters so short that not enough of them is left to give the clamping plates a firm bearing on them. Such a cutter sometimes flies out of the machine, subjecting everyone in the vicinity to the liability of serious injury. I have avoided this 85 objection by marking the cutter to indicate the safe limit of grinding. In the cutter shown, the mark mutilates the cutter so as to destroy any cutting edge passing through 90 the point of mutilation. This is accomplished very simply in the cutter shown by making two holes 28, extending into the body of the cutter through one of the faces that form the cutting edge. When the cutter is ground back to the location of the holes, if the operator neglects the warning 95 that the safe limit of grinding has been reached, the cutting edge will be destroyed by the mutilation, and he would have to 100 grind clear through the holes (about $\frac{1}{4}$ inch in the cutter shown) before he could get a complete operative cutting edge. This wastes so much time that he will secure new cutters in preference. The holes 28 are so 105 located that enough of the cutter 30 remains behind them to give the clamping plates a firm grip, thus avoiding the danger of a cutter flying out and injuring someone.

Having described my invention, what I 110

claim as new and desire to secure by Letters Patent of the United States is:—

1. In combination, a cutting blade and a holder therefor comprising clamping means 5 constructed to clamp the blade edgewise throughout its length, said blade having a localized irregular formation so located as to leave the cutting edge initially intact but to render the cutting edge unfit for its intended use when it has been ground back so 10 far as to deprive the blade of a safe clamping length.

2. A cutting blade for trimming machines, having a cutting edge, clamp-engaging faces 15 extending from opposite ends of said cutting edge to the rear end of the blade, and a localized irregular formation between said clamp-engaging faces and placed so as to leave said cutting edge intact until, by 20 grinding back the blade to sharpen said edge, said clamp-engaging faces are deprived of adequate clamping length.

3. A cutting blade having a cutting edge

and clamp-engaging faces extending from opposite ends of said cutting edge to the 25 rear end of the blade, all the marginal portions of the blade being integral but the blade having a mutilation surrounded by said marginal portions and located so as to destroy the cutting edge for its intended 30 purpose when said edge has been ground back so far as to impair the safety of the blade.

4. A cutting blade having an integral principal face and a non-integral principal 35 face the integrity of which is impaired by a depression wholly within the margins of the blade, the first said face being beveled so as to form a cutting edge at the other said face, said depression being arranged to 40 destroy said cutting edge for its intended purpose when said edge has been ground back to a line intersecting the depression.

In testimony whereof I have signed my name to this specification.

HENRY M. LOOMER.
